SCRAPER

John M. Corbett, Huntington Park, and Robert Bruce Magee, Los Angeles, Calif., assignors, by mesne assignments, to The Buckeye Traction Ditcher Company, Findlay, Ohio

Application July 18, 1938, Serial No. 219,806

7 Claims. (Cl. 37—126)

Our invention relates to earth scrapers of the type adapted to gather earth from a surface over which the scraper is being moved, to carry the earth to a location where it is desired to dump the same, and to dump the earth at the desired location.

It is an object of our invention to provide an earth scraper of the character described which includes a main bowl and an auxiliary bowl or apron which cooperates with the forward part thereof in order that the main bowl may be completely filled, thus enabling the scraper to carry relatively large loads.

It is one of the objects of our invention to provide a unique apron operating means whereby the apron is moved into loading, carrying, and dumping positions in response to corresponding positions of the main bowl.

It is a further object of our invention to provide a simple apron operating means in which a cam and engager arrangement is employed which is of sturdy fool-proof construction.

It is another object of our invention to provide an earth scraper in which the main frame is pivoted around rear wheels and in which the forward part of the main frame is raised and lowered in order to bring the blade of the scraper into proper operating position, the control means therefor being preferably a cable and sheave arrangement.

It is another object of the invention to provide a scraper in which the bowl is operated by a cable and is moved thereby into carrying, digging, and dumping positions.

It is a still further object of our invention to provide a scraper in which the bowl is moved into its various digging positions by a cable, and in which the bowl when in digging position is supported by the cable and when in carrying position is lowered into engagement with the frame so that during carrying position the cable is not required to take any load.

It is an additional object of our invention to provide a scraper of the general character pointed out above in which the main frame is pivoted on wheels at its rearward part and is vertically adjustable on a forward carriage structure, which carriage structure has wheels which are movable in response to undulation in the surface over which the scraper is being moved, and in which the front wheels do not in any way affect the horizontal position of the main frame.

It is a still further object of our invention to provide a scraper in which the bowl is returned from dumping position to digging or carrying po-

sition by the action of gravity and in which auxiliary means is provided for initiating the downward movement of the bowl.

In the following detailed description we will describe a preferred form of our invention. This form of our invention includes in combination the various elements and sub-combinations comprising our invention. Other structures may be designed incorporating the features of our invention, and we therefor do not wish to be limited to the details of construction disclosed herein, it being understood that this form of our invention has been chosen solely for the purpose of instructing those skilled in the art as to how our invention may be practiced.

Further objects and advantages of the invention will be brought out in the following part of the specification.

Referring to the drawings which are for illustrative purposes only:

Fig. 1 is a side elevation showing the scraper in digging or scraping position.

Fig. 2 is a side elevation showing the scraper in carrying position, the dumping position of the scraper bowl being shown in dotted lines in this view.

Fig. 3 is a plan view of the scraper in digging position.

Fig. 4 is a front elevation of the scraper showing the apron thereof in lowered position prior to the raising of the scraper frame to carrying position.

Fig. 5 is a rear elevation of the scraper in scraping position, the left-hand portion of this view being sectioned on a plane indicated by the line 5—5 of Fig. 1.

Fig. 6 is an enlarged fragmentary sectional view taken as indicated by the line 6—6 of Fig. 3.

Fig. 7 is an enlarged fragmentary sectional view similar to Fig. 6 but showing the apron operating cam assembly in position assumed when the apron is lowered.

Fig. 8 is an enlarged fragmentary section taken as indicated by the line 8—8 of Fig. 4.

Fig. 9 is an enlarged section taken as indicated by the line 9—9 of Fig. 1.

Fig. 10 is an enlarged fragmentary sectional view taken as indicated by the lines 10—10 of Figs. 3 and 1.

Fig. 11 is a fragmentary sectional view taken as indicated by the lines 11—11 of Figs. 1 and 3.

Fig. 12 is an enlarged fragmentary section taken as indicated by the line 12—12 of Fig. 3.

Fig. 13 is a fragmentary section taken as indicated by the line 13—13 of Fig. 12.

The present invention includes a rugged frame 15 which travels on wheels 16 and 17, a laterally directed scraper blade 18 which is adapted to engage the ground when the device is in working position, as shown in Fig. 1, a bowl 19 which receives the load of earth or similar material which passes over the blade 18 when the device moves forwardly, an auxiliary load carrying member or apron 20 for obstructing the mouth of the bowl 19 when the device is in carrying position, as shown in Fig. 2, elevator means 21 for raising the front end of the frame 15 from its position of Fig. 1 to its position in Fig. 2, bowl operating means 22 for moving the bowl 19 through the working, carrying, and dumping positions thereof, and apron operating means 23 for moving the apron 20 from its lowered position, as shown in Fig. 2, to its raised position in Fig. 1.

As shown in Fig. 3, the frame 15 includes fabricated side means symmetrically formed in right and left-hand relation. These side means 24 each include a front portion 25 extending rearwardly and outwardly from a head 26. The portions 25 constituting the forward ends of the beams 24 are fabricated from flat steel plates so as to be of hollow rectangular cross-section. Parallel and essentially horizontal side portions 27 extend rearwardly from the ends of the diagonal portions 25, these side portions 27 being likewise fabricated from steel plates welded together so as to form tubular structural elements varying in cross-section, as shown in Figs. 1 and 3, and having their rear ends 28 connected to vertical posts 29, from the lower portions of which foot portions 30 rearwardly extend, and on the rearward ends thereof carry brackets 31 which in turn carry axles 32 in inward projecting relation to support the rear wheels 17.

As shown in Fig. 10, the large front part of each side portion 27 includes a top plate 33, a side plate 34, a bottom plate 35, and an inner side plate 36 which is cut away at 37, and of which the cut-away portion is replaced by the upper corner 38 of a guard plate 39, the upper portion of which extends back, as indicated at 40 in Fig. 11, so as to form the inner wall of the rear part 27a of the side portion 27. The rear part 41 of the guard or gusset plate 39 extends to and enters into the formation of the rear post 29, and the lower part 42 of the plate 39 extends below the post 29, and at a distance ahead of the post 29 carries one end of a horizontal shaft 43. The scraper blade 18 has its ends connected to the lower portions of the plates 39 in a position forward of the shaft 43. The blade 18 comprises a reversible and replaceable plate 44, as best shown in Fig. 12, which is secured by means of screws 45 to the permanent supporting structure 46 of the blade 18, which supporting structure is fabricated by welding together of steel plates. The front edge 47 of each plate curves downward and rearward from the upper forward corner thereof to a point adjacent the lower edge of the scraper blade 18. As will be seen in Figs. 1, 10 and 12, a triangular portion 48 of each guard plate 39 is flared outwardly and laterally to form guide plates which converge rearwardly toward the blade 18 to guide materials thereto. A reinforcing member 49 is welded to the exterior of each guard plate 39 in a position near the lower edge thereof and extending substantially horizontally, this reinforcing member 49 comprises a plate bent to form a structural angle having an upper leg 50, Fig. 11, which is shorter than the lower leg 51 there-

of. This angle member 49 is placed against the plate 39 with the webs or legs 50 and 51 thereof lying against the face of the plate 39 and with the corner 52 thereof projecting outwardly. The member 49 extends across the lower end of the post 29 and to the rear end of the foot portion 30 where its legs 50 and 51 are welded to that portion of the plate 39, identified by numeral 53, which extends rearwardly beyond the lower part of the post 29 and forms the vertical web of the rearwardly extending foot portion 30. From the rear face of the post 29 a steel channel 54 slopes downward to meet the bracket 31 at the rear end of the foot portion 30, this channel 54 being welded to the rearwardly extending portion 53 of the side plate 39, as shown in Fig. 1. As best shown in Fig. 5, a structural channel 55 is extended laterally across the back of the frame 15, between the foot portion 30, the ends of this channel being welded at 56 to the inner faces of the foot portions 30. Diagonally placed I-beams are welded to the lower face of the channel 55 and to the lower parts of the foot portions 30 in positions to form diagonal struts. On the inner faces of the rearward parts of the foot portions 30 angle members 49a, symmetrical to the angle members 49, are welded in cooperating relation to the rear ends of the members 49 to stiffen the rear ends of the foot portions 30. As shown in Figs. 1 and 10, curved angles 58 are secured to the forward portions of the guard plates 39 adjacent the curved edges 47 thereof and extending upwardly from the forward ends of the reinforcing members 49, there being wear plates 59 removably secured to the lower ends of the angles 58. The center portion of the frame 15 is reinforced by the lateral box beam 60 which is disposed substantially centrally between the head 26 and the posts 29. The bowl 19, as shown in Fig. 12, has a tube 61 at its forward lower edge, by which it is hinged on the lateral shaft 43. This bowl 19 includes a bottom wall 62, a back 63, and side walls 64 comprising plates having sloped forward edges 65 which are flared outwardly to form lips which lie in close proximity to the guard walls 39, as shown in Fig. 11. The bottom and back walls 62 and 63 are formed from a pair of steel plates 66 and 67 bent, as indicated at 68, and being supported in spaced relation by use of filler members 69 and 70, which filler members are preferably structural channels and wood strips, as shown in Fig. 13. At the upper edge of the wall 63 an I-beam 71 is secured, end portions of the same being cut away to accommodate sheaves 72 and 73, as shown in Figs. 3 and 12. At each end of the beam 71 a pulley block 74 is secured to the bowl 19, these pulley blocks 74 having sheaves 75, 76, 77, and 78, as shown in Fig. 3, over which cable means 79 is passed, and which cable means is operative to swing the bowl 19 on the lateral shaft 43. The sheaves 72 and 73 serve as cross-over pulleys between the blocks 74, and aligned with the lower edges of the sheaves 72 and 73 there is a guide tube 80 for the transverse portion of the cable means, as also shown in Fig. 5.

The apron 20 comprises a curved lower wall 81, a pair of end plates 82, and a pair of arms or levers 83 extending, as shown in Fig. 2, in upward and rearward direction to pivot pins 84 mounted within the rear portions 27a of the side members 27 constituting the portions of the frame 15. The lever arms 83 consist of flat plates which lie outside the guard plates 39 and in spaced relation

thereto, as shown in Figs. 10 and 11, and the arms are of such length that the inner or lower edge 85 of the apron 20 will follow along the curve defined by the edges 47 of the guard walls 39 when the arms 83 are swung upwardly from their position in Fig. 2 to the position thereof in Fig. 1. When the apron 20 is in lowered position the lower edge 85 thereof will overlie the lower portion of the scraper blade 18, as shown in Fig. 2, and the apron 20 will serve as a gate across the mouth of the bowl 19 to prevent spillage of any portion of the load therefrom while the device is being moved to a location wherein it is desired to dump the load.

The arms 83 are cut from flat plates 86 and have upwardly bent portions 87 at their upper ends, to the inner faces of which oval plates 88, as shown in Figs. 7 and 11, are secured in spaced relation by means of walls 89 which are perpendicular to the faces of the plates 86 and 88. The pivot pins 84, which are carried by the frame 15, pass through the upper ends of the plates 86 and 88. The plates 86 are further reinforced by means of angles 90 which are welded to the inner faces thereof in positions, such as indicated in Fig. 7. Between the plates 86 and 88, in a position spaced below the hinge pins 84, pins 91 are extended, these pins engaging the forward ends of links 92 forming a part of the apron operating means 23, such links 92 passing through openings 93 in the vertical posts 29, as shown in Figs. 6 and 7. The links 92 cooperate with cam members 94 to form toggle means operative to swing the levers 83 from their positions in Figs. 2 to their positions in Fig. 1.

The cam members 94 each include a boss 95 having a lateral opening to receive a pivot pin 96 carried between plates 97 which project upwardly from the foot portions 39 of the frame. In spaced relation to the pin 96, the member 94 carries a crank pin 98 which passes through a slot 99 in the rear end of a link 92. The cam member 94 has a notch or pocket 100 adapted to be engaged by a projection 101 which extends laterally from the bowl 19 during specified portions of the movement of the bowl, the purpose of this engagement being to rotate the cam member 94 between the positions thereof shown in Figs. 1, 2, 6, and 7. In Figs. 1 and 6 the bowl 19 is shown in scraping position. At this time the bowl 19 is raised so that the projections 101 are raised from their lowermost position and are disposed at the mouths of the pockets 100. The rear ends of the links 92 are at this time in engagement with stops 102, and the crank pins 98 are nearly aligned with the pins 91 and 96, so that the toggles, of which the links 92 form a part, are extended and the lever arms 83 are held in raised position. It will be noted that, as shown in Fig. 6, the centers of the crank pins 98 are below lines *a*—*b* extended through the centers of the pins 91 and 96, so that the end thrust exerted against the links 92 by the pins 91 will tend to break the toggles downward, thereby holding the same firmly against the stops 102. Should it now be desired to lower the apron 20 from raised position, as shown in Fig. 1, to lowered position, as shown in Fig. 2, the bowl 19 is merely allowed to rotate downwardly and rearwardly from its position of Figs. 1 and 6 to the position thereof shown in Fig. 7. The projections 101, which are preferably flanged rollers mounted on laterally projecting shafts 103, move from the position thereof in Fig. 6, as indicated by the arrow 104, to the position thereof in Fig. 7.

During this movement the projections 101 will engage the rear walls 105 of the pockets 100 and will cause rearward rotation of the cam members 94, carrying the crank pins 98 upwardly and rearwardly from their position of Fig. 6 to the position shown in Fig. 7, thereby permitting the links 92 to swing rearwardly, which movement is accompanied by a downward movement of the arms 83 to carry the apron 20 into engagement with the blade member 18.

The mouth of the bowl 19 will now be closed and the scraper may be converted to carrying position by raising the forward end of the frame 15 by use of the elevator means 21 in a manner 15 to be hereinafter described, thereby swinging the frame 15 upwardly around the axis of the rear wheels 17 into raised position, as shown in Fig. 2, at which time the scraper blade 18, the apron 20, and the bowl 19 will be raised from the ground level 106. When the scraper device has been moved to desired position for dumping, this may be accomplished without lowering the frame 15 by merely rotating the bowl 19 upwardly from carrying position thereof shown in Fig. 2 to raised or dumping position indicated by dotted lines 107. This movement of the bowl 19 will automatically raise the apron 20 to the position thereof indicated by broken lines 108. During the first part of the upward movement of the bowl 19, the projections 101 move upwardly from their position shown in Fig. 2 and Fig. 7 through the position thereof shown in Fig. 6. Referring to Fig. 7, as the projections 101 are carried upwardly they are brought into engagement with the front walls 109 of the cam members 94, causing the cam members 94 to swing forwardly and carry the crank pins 98 forwardly and downwardly toward the stops 102, thereby moving the links 92 and the levers 83 into the positions thereof shown in Fig. 6. At this time the toggles consisting of the links 92 and portions of the cam members 94 will be extended and will be deflected below the line *a*—*b* of Fig. 6 so as to be locked in such extended position. At the same time the mouths of the pockets 100 will be spaced upwardly so that as the upward movement of the bowl 19 is continued the projections or cam engagers 101 will move upwardly and forwardly, as indicated by the arc 109 of Fig. 6. Whenever the projections 101 are in or above the position thereof shown in Fig. 6, the apron operating mechanism will be in actuated condition.

After the load is dumped, the bowl 19 may be 55 swung back from the dumping position 107 thereof to scraping position as shown in full lines in Fig. 1, at which time the projections 101 will be ready for engagement with the walls 105 of the pockets 100, so that after a load has been picked up by the bowl 19 the apron 20 may be lowered 60 merely by dropping the bowl 19 from its position of Fig. 1, thereby causing release of the apron operating mechanism as described relative to Figs. 6 and 7. To cause positive rearward movement of the bowl 19 from the position thereof as shown in dotted lines 107 of Fig. 2, springs 110 are supported by the cross-beam 60 by use of brackets 111, as shown in Fig. 10, and in such position that the upper ends of these springs 110 will be engaged by plates or brackets 112 secured to the side walls 64 of the bowl 19, as shown in Figs. 1 and 3. As the bowl 19 is swung into fully raised position, as indicated by dotted lines 107 in Fig. 2, the springs 110 will be engaged by the plates 112 and will be thereby compressed so that

they will thereafter exert against the bowl 19 a force tending to swing the same in a rearward direction when the pull exerted by the cable means 19 is slackened off.

As shown in Fig. 4, the front wheels 16 are carried at the ends of an axle 113 which has a draft bar 114 extending forwardly therefrom and having its forward end adapted for attachment of a draft clevis 115. The shaft or axle 113 is mounted for rotation relative to two axes, namely, a vertical axis, to give the axle 113 a steering movement, and a horizontal axis extending transversely through the center of the axle 113 so that the wheels 16 may move up and down in opposite directions as the same pass over uneven ground. A pin 116 passes through substantially the center of the axle 113 from front to rear thereof, and the ends of such pin are received in bosses 117 carried by the side plates 118 of a head 119 adapted to rotate on a vertical axis. The upper part of the head 119 includes a thrust plate 120 from which a pin 121 extends upwardly into a vertical tube 122 which is secured within the lower end of the vertical post or column 123 by means of spacer blocks 124, as shown in Figs. 8 and 9.

The column 123 is of hollow square cross-section, and as shown in Figs. 2 and 9, consists of a pair of structural angles 125 placed with the flange edges 126 thereof in engagement, and being secured by welds 127 between the adjoining flange edges. Slide plates 128 are secured to the side faces of the column 123.

The head 26 at the forward end of the frame 15, as shown in Figs. 1, 2, 4, and 9, comprises a pair of heavy side plates 129 and 130 which extend vertically on opposite sides of the column 123 and have slide plates 131 secured therein for engagement with the slide plates 128 of the column 123. The diagonal members 25, forming the front part of the frame 15, are welded to the side plates 129 and 130, as indicated by the numeral 132.

The plates 129 and 130 have portions 133' and 133 which project rearwardly beyond the plane defined by the rear face 134 of the column 123. Across the rear edges of these plates 129 and 130 a back plate 135 is secured, this back plate having projecting flange portions 136. In the space 137 between the rear face 134 of the column 123 and the back plate 135 a pair of rollers 138 are mounted so as to roll in engagement with the rear face 134 as the head 26 moves vertically on the column 123. These rollers 138 have projecting shafts 139 which extend through openings in the plate portions 132 and 133 and engage bearing blocks 140 which are horizontally slidable in housings 141 and are moved toward the column 123 by wedge blocks 142 which are vertically movable and have studs 143 which project out through vertical slots in the extending portions 136 of the back plates 135, nuts 144 being provided to clamp the wedge blocks 142 in desired position.

The side plates 129 and 130 also have forwardly projecting portions 145 and 146 which extend forwardly of the plane defined by the front face 147 of the column 123. A pair of horizontal shafts 148 are extended across the space between the plates 129 and 130 in such position that these shafts 148 may support rollers 149 in engagement with the front face 147 of the column 123, such rollers 149 being preferably positioned near the upper and lower edges of the plates 129 and 130, as shown in Fig. 1. A front plate 150 is ex-

tended across the front edge of the side plate 129 in a position substantially parallel to the front face 147 of the column 123, this plate 150 being in spaced relation to the front face 147 and being welded to the front edge of the plate 129 and to the side of the projecting portion 146 of the plate 130. A plate 151 is welded between the plates 129 and 130 between the rollers 149. A substantially horizontal pin 152 is supported by the plates 150 and 151 and carries thereon sheaves 153 and 154 which form a part of the elevator mechanism 21 for lifting the head on the column 123. To cooperate with the sheaves 153 and 154, sheaves 155, 156, and 157 are mounted at the upper end of the column 123 by means of a platform 158. These sheaves 155, 156, and 157 are carried in a housing 158'; the first sheave 155 is set diagonally, and the sheaves 156 and 157 are placed substantially parallel to the front face 147 of the column 123. As shown in Fig. 9, a lead-in sheave 159 is mounted on a swinging bracket 160' carried by a support 161 which is secured to the far side of the front plate 150 of the head 26. For operation of the elevator means 21 a cable 160 is carried back from a suitable winch on the tractor which pulls the scraper device, this cable being carried under the sheave 160a and bent upward at 161', Fig. 1. The cable is passed over the sheave 155 and down and around the sheave 153, as indicated at 162. As indicated at 163 in Figs. 4 and 9, the cable is passed up from the sheave 153 to, and then over, the sheave 156, from whence it is carried down, as indicated at 164, to the sheave 154. The cable 35 is then passed under the sheave 154 and thence up and over the sheave 157, the end 165 of the cable then being carried down from the sheave 157, as shown in Fig. 1, to a suitable anchor 166 at the side of the head 26. When it is desired to lift the front end of the frame 15, the cable 160 is pulled forward, as indicated by the arrow 167 in Fig. 1, with the result that the loops of cable extended over the sheaves 153 to 157 are shortened, exerting a lift on the lower sheaves 153 and 154 which is transmitted through the pin 152 to the head 26, lifting the same under control of the operator, so as to raise the frame 15 from its position of Fig. 1 through any desired intermediate position, to its fully raised position of Fig. 2, which is referred to as the carrying position of the device.

In addition to the sheaves 72, 73, 75, 76, 77, and 78 which are mounted on the upper rear part of the bowl 19, the bowl operating means 22 includes sheaves 168 and 169 which are mounted on the near side of the frame 15, sheaves 170 and 171 which are mounted on the far side of the frame 15, a lead-in sheave 172 mounted in a diagonal position ahead of the sheaves 168 and 169 so as to lead a cable to sheave 168, and lead-in sheaves 173 and 174 which are mounted on the head 26 in the positions shown in Figs. 1, 3, 4, and 9. The lead-in sheave 174 is carried in a clevis 175 which swings on a vertical axis in a bracket 176, Fig. 9. The cable 79 of the bowl operating means 22 is led from a suitable winch carried by the tractor to the lead-in sheave 174, as indicated at 175'. The cable passes under the sheave 174 and thence upward at 176' to the sheave 173. It passes over the sheave 173 and thence forward at 177 to the sheave 172. From the lead-in sheave 172 the cable passes up and over the sheave 168, from whence it is continued forward at 178 to the sheave 75. It is passed down around the sheave 75 and back at 179 to

the lower part of the sheave 169, and is then carried up and around the sheave 169 and brought forward at 180, Fig. 3, to the upper part of sheave 16. The cable is then passed down from the sheave 16 and then under the sheave 12, to be carried across at 181 through the guide tube 80, Fig. 5, to the lower part of the sheave 13, under which the cable is then carried to the sheave 11, as indicated at 182, Fig. 5. As shown in Fig. 3, the cable is carried up over the sheave 11 and then forward at 183 to the sheave 170. The cable is then carried down around sheave 170 and is brought rearward at 184 to the under part of sheave 18 over which it is passed and then carried forward at 185 to sheave 171. After being passed down over the sheave 171, the cable is carried rearward at 186 to an anchor 181, Fig. 5, which is carried by the bowl 19. When the cable 79 is in effect shortened by pulling forward on the front end 175 thereof, the loops of cable extending over the sheaves 15, 16, 17, and 18, 168, 169, 170, and 171 will be shortened and the bowl will be swung forward and upward to an extent determined by the shortening of these cable loops.

Although we have shown a workable and commercial form of our invention, it will be recognized that certain parts or elements thereof may be replaced by other parts of equivalent function without departing from the spirit of the invention; therefore, the invention is not limited to the details of the foregoing disclosure but should be accorded the full scope of the following claims.

We claim as our invention:

1. In an earth working device of the character described, the combination of: a frame member; a bowl member mounted on said frame so as to be moved between working position and carrying and dumping positions; means for so moving said bowl member; an auxiliary load carrying member mounted so as to have movement between operative and inoperative positions relative to said bowl member; and means disposed so as to be out of operative engagement with said bowl when the same is in said dumping and working positions and so as to receive movement from said bowl member as the same is moved between said working position and said carrying position and to transmit said movement to said auxiliary member to accomplish movement thereof between said inoperative and operative positions.

2. In a scraper device of the character described, the combination of: a frame member; a bowl member mounted on said frame member so as to be moved from working position to a carrying position; an apron mounted on said frame member so as to be moved between lowered position and raised position relative to said bowl member; toggle means for moving said apron between raised and lowered positions, said toggle means comprising a first link member pivotally connected to said apron and a second link member pivotally connected to said first link member and to said frame member; and means carried by said bowl member so as to engage said toggle means and actuate the same whereby it will move said apron between said raised and lowered positions in consequence of the movement of said bowl member.

3. In a scraper device of the character described, the combination of: a frame member; a bowl member mounted on said frame member so as to be moved from dumping position to working position and from working position to a carrying position; an apron mounted on said frame member so as to be moved between low-

ered position and raised position relative to said bowl member; toggle means for moving said apron between raised and lowered positions, said toggle means comprising a first link member pivotally connected to said apron and a second link member pivotally connected to said first link member and to said frame member; and means carried by said bowl member so as to engage said toggle means as said bowl member moves between said working position and said carrying position to actuate said toggle means whereby it will move said apron between said raised and lowered positions in consequence of the movement of said bowl member.

4. In an earth working device of the character described, the combination of: a frame member; a bowl mounted on said frame member so as to be moved from an intermediate working position upward to dumping position and downward to carrying position; an engager moving with said bowl; means for moving said bowl between said positions; an apron mounted so as to have movement between raised and lowered positions relative to said bowl member; and means holding said apron in said raised position when said bowl is in said dumping and working positions, said means being disposed out of engagement with said engager when said bowl is in said dumping position and being actuated by the movement of said engager as said bowl is moved downward from said working position to said carrying position.

5. In a scraper device of the character described, the combination of: a frame member; a bowl member mounted on said frame member so as to be moved from dumping position to working position and from working position to a carrying position; an apron mounted on said frame member so as to be moved between lowered position and raised position relative to said bowl member; toggle means for moving said apron between raised and lowered positions, said toggle means comprising a first link member pivotally connected to said apron and a second link member pivotally connected to said first link member and to said frame member; and a member moving with said bowl member so as to engage said toggle means as said bowl member moves between said working position and said carrying position to actuate said toggle means whereby it will move said apron from raised to lowered position as said bowl member is moved from working position to carrying position, said member being out of engagement with said toggle means when said bowl member is raised above said working position.

6. In an earth working device of the character described, the combination of: a frame member; a bowl member mounted on said frame member so as to be moved between working position and carrying and dumping positions; cable means operative to so move said bowl member; an auxiliary load carrying member mounted so as to have movement between operative and inoperative positions relative to said bowl member; and cam means disposed so as to be disengaged from said bowl when the same is in its working and dumping positions and to hold said auxiliary member in inoperative position when said cam member is disengaged from said bowl, said cam means being operative by the movement of said bowl member from said working to said carrying position to move said auxiliary member from said inoperative position to said operative position.

7. In a scraper device of the character described, the combination of: a frame member; main load carrying member mounted on said frame member so as to be moved directly from an extreme dumping position to an intermediate working position and from working position to an extreme carrying position; means for so moving said load carrying member; an auxiliary load carrying member supported so as to be movable from inoperative position to operative position; and means normally holding said auxiliary

member in said inoperative position when said main load carrying member is in said dumping and working positions, and being operative only in consequence of movement of said main load carrying member from said working position to said carrying position to move said auxiliary load carrying member from inoperative to operative position.
